METAL CONTAINER

William W. Hodgson, Chicago, Ill., assignor to
 Continental Can Company, Inc., New York,
 N. Y., a corporation of New York

Application April 22, 1935, Serial No. 17,715

1 Claim. (Cl. 220—27)

The invention relates to new and useful improvements in a metal container of the friction closure type and more in particular to a container wherein a frangible sealing member is used in conjunction with a friction closure.

An object of the invention is to provide a container of the above type wherein a frangible sealing member is joined to a carrier ring and said carrier ring is hermetically attached to said can top by frictional contact therewith, whereby said carrier ring and frangible member may be removed as a unit and replaced should the frangible member become ruptured during manufacture of the container.

15 Referring to the drawings:

Fig. 1 is a view partially in side elevation and partially in section of the preferred form of the invention.

Fig. 2 is an enlarged sectional view of a portion of Fig. 1.

20 Fig. 3 is an enlarged sectional view of Fig. 1 showing the carrier ring and sealing disc therefor removed as a unit.

Fig. 4 is an enlarged sectional view of a slightly modified form of container embodying the invention.

Fig. 5 is an enlarged sectional view of a further modification embodying the invention.

The invention relates particularly to a metal container of the friction closure type having a frangible sealing member used in conjunction therewith. The container comprises a body portion preferably of metal and having ends double seamed thereto, one of said ends being in the form of a can top having a central opening and a vertical friction wall surrounding said opening. The can top has a portion of the metal adjacent the friction wall shaped so as to form a retaining recess for sealing material. A carrier ring is provided for the container having a portion thereof frictionally engaging the vertical wall of the can top and a portion thereof overlying the recess formed adjacent thereto. A frangible sealing disc is used for closing the opening in the carrying ring, the lower portion of said ring being so shaped as to clamp the peripheral edge of the sealing disc for joining the same thereto. A sealing compound is interposed between the carrier ring and the sealing disc and between the can top and the carrier ring for hermetically closing the container, and a friction closure which is adapted to overlie and protect the frangible disc against accidental rupture is used for further closing the container.

In all forms of the invention, should the frangible disc become ruptured during the manufacture of the can, the carrier ring and ruptured disc could be removed as a unit and replaced without destroying the rest of the 5 container.

Referring to the drawings and more in particular to the preferred form of the invention shown in Figs. 1, 2 and 3, a container embodying the invention is indicated at 5. The container is preferably of metal comprising a body portion 6 having a bottom end 7 double seamed thereto as indicated at 8 and a top end 9 secured thereto by the double seam 10. The top end 9, or can top as it is usually called, has a central 15 opening with a vertical friction wall 11 surrounding said opening. A friction closure 12 is used for closing the container, said friction closure having a vertical friction wall 13 which is adapted to be forced into engagement with 20 the friction wall 11 of the can top. The closure 12 has a laterally extending bead 14 at its upper end beneath which a tool may be placed for removing the same from the container.

The can top 9 has the portion 15 thereof shaped to form a retaining recess 16 which is adapted to receive a sealing compound 17. A carrier ring 18 is formed with a wall 19 which is adapted to frictionally engage the wall 11 of the can top whereby the carrier ring and 25 the can top are firmly held together as a unit. The carrier ring has a portion overlying the recess 16 formed in the can top and contacting with the sealing material 17 placed therein so as to provide an hermetic seal between the carrier ring and the can top. A frangible sealing disc 20 is provided for closing the opening in said carrier ring. The lower portion of said ring is shaped so as to form clamping members 21 and 22 for gripping the peripheral edge portion 40 23 of the sealing disc and fixedly securing the same to the carrier ring. A sealing compound 24 is placed between the edge portion of the sealing disc and the clamping members of the carrier ring for establishing an hermetic seal 45 between the sealing disc and the carrier ring.

The sealing disc is attached to a carrier ring and the ring placed in the can top by the manufacturer. The container is filled by the packer through the bottom end, after which it is closed. 50 If the frangible sealing disc becomes ruptured during the manufacture of the container, the carrier ring can be reached through the bottom of the container, forced out and replaced by another. This permits the salvaging of the 55

greater portion of the container when the frangible disc is accidentally ruptured.

In the modified form of the invention shown in Fig. 4 of the drawings, the construction of the can top differs slightly from that shown in Figs. 1, 2 and 3. The portion 15b of the can top is extending inwardly at right angles to the friction wall 11 thereof and an annular recess 17a is formed therein which is spaced inwardly 5 from said friction wall. The recess 17a is adapted to receive a sealing compound 16a and a portion of the carrier ring 18 is shaped as indicated at 18a to conform to the recess and contact with the sealing material for establishing an hermetic seal between the retainer ring and the container top.

In the modified form of the invention shown in Fig. 5 of the drawings, the can top 9 is formed with a recess 17b for receiving the sealing compound located between the vertical friction wall 11 and the can body. The friction wall 19 of the carrier ring has a portion 19b which extends laterally from the upper end thereof and overlies the recess 17b. This portion of 20 the carrier ring is shaped so as to contact with and compress the sealing material within the recess, thus establishing a tight seal. The outer peripheral edge 19c of the carrier ring is dimensioned so as to have frictional engagement with 25 the vertical wall 9b of the can top, thus firmly securing the carrier ring to the can top and in contact with the sealing material. By the construction shown in this modified form of the invention, the clamping members for the frangible sealing are brought closer to the friction wall 11 of the can top and therefore a larger opening may be provided in a can of standard 30 dimensions.

When it is desired to open the container, the 35 friction closure is pried out and the frangible sealing disc is cut away by a knife or other sharp instrument. The friction closure may be used for reclosing the container after the inner seal has been removed. If a customer when pur- 40 chasing the container finds the inner seal rup-

tured, it is an indication that the container has been tampered with and possibly some of the contents removed, or replaced with a substitute, or diluted. Furthermore, while a friction plug closure forms a fairly tight seal, the use of a 5 frangible metal seal in the construction as described produces an hermetically sealed package.

From the above, it will be apparent that a container of the friction closure type has been devised wherein an hermetic seal has been established and wherein a carrier member and sealing disc have been formed as a unit which may be replaced should the frangible seal become ruptured during the manufacture of the can, thus saving the necessity of scrapping the remainder 10 of the container.

It is obvious that minor changes in the details of construction and the arrangement of parts may be made without departing from the spirit of the invention as set forth in the appended 15 claim.

Having thus described the invention, what I claim as new and desire to secure by Letters Patent, is:—

A metal container comprising a body portion 25 having a can top secured thereto, said can top having a central opening and a vertical friction wall surrounding said opening, said can top having an inwardly projecting ledge at the lower end of said vertical friction wall shaped so as to provide a retaining recess for a sealing material, a carrier ring frictionally engaging the lower portion of said vertical friction wall of the can top and held thereto in contact with the sealing material in said recess, the upper 30 portion of said vertical wall being adapted to receive a friction plug, said carrier ring having a portion thereof extending inwardly beyond the inner edge of said ledge, a frangible sealing disk for closing the opening in said ring, the inwardly 35 projecting portion of said ring being shaped so as to provide a recess for a sealing material and so as to clamp the peripheral edge of the sealing disk against the sealing material in said recess.
